UNITED STATES PATENT OFFICE.

HENRY M. SHEER, OF QUINCY, ILLINOIS, ASSIGNOR TO H. M. SHEER COMPANY, OF QUINCY, ILLINOIS, A CORPORATION OF ILLINOIS.

MAINTAINED-OIL-LEVEL-REGULATING DEVICE.

Application filed March 10, 1921. Serial No. 451,388.

To all whom it may concern:

Be it known that I, HENRY M. SHEER, residing at Quincy, in the county of Adams and State of Illinois, a citizen of the United States, have invented certain new and useful Improvements in Maintained-Oil-Level-Regulating Devices, of which the following is a specification.

This invention relates to maintained oil level regulating device, and the like.

The object of my invention is to maintain a constant, uniform, and unobstructed flow of oil to the burner.

A further object of my invention is to construct an oil controlling device which is to be placed beneath the oil reservoir, which will maintain a constant level in the burner.

A further object of the invention is to arrange a reservoir in the oil controlling device with such relation to the base supporting them that the moving of the reservoir proper up or down will regulate the height of the oil in the burner.

A further object of the invention is to arrange a sight feed adjacent the burner, whereby the operator may readily see the height of the oil in the chamber adjacent the burner preparatory to starting the device.

In the accompanying drawings:

Fig. 1 is an elevation partly in section disclosing my heating system complete;

Fig. 2 is an enlarged transverse section of the controlling mechanism;

Fig. 3 is a top plan view of the burner and visible feeding device adjacent thereto;

Fig. 4 is a modified form of the reservoir;

Fig. 5 is a modified view on the line 5—5 of Fig. 1 of the oil feed-pipe adjacent the burner.

The numeral A indicates the main supply tank; B, the auxiliary supply tank or reservoir; C, the valve controlling mechanism; and D, the burner. The auxiliary reservoir or supply tank consists of a cylindrical receptacle divided into upper and lower compartments 1 and 2, being separated by a transverse disk 3. The upper end of the compartment 1 is open and adapted to receive the main supply tank A, while at the bottom thereof is arranged a screen or netting spaced therefrom and supported upon a cylindrical flange member 5. Immediately above the screen 4 is placed a filtering medium 6, preferably consisting of a

heavy cloth, over which is placed a quantity of cotton batting or other similar material 7.

The partition 3 is provided centrally thereof with a downwardly projecting nipple 8, having a small central opening 9 terminating at the lower end thereof in a valve-seat 10. The numeral 11 indicates a float constructed of cork or other suitable material located in the lower compartment 2. In the central opening 12 of the float is arranged a valve-stem 13 made integral with a metal disk 14, the latter being secured to the lower side of the float 11 and provided concentrically with a stem 13 and with a plurality of openings 15. The upper end of the valve-stem 13 is countersunk and adapted to receive a high-grade perfect steel ball-valve 16, the ball adapted to seat itself about two-thirds of its diameter in the valve-stem 13. By this construction, when the fuel has risen a sufficient height in the lower compartment, the ball-valve will act to cut off the supply from the upper compartment.

The auxiliary reservoir is preferably supported upon a base 17 provided with a hollow threaded portion 18 adapted to receive the hollow threaded stem 19 secured to the bottom of the reservoir 1 by a reinforcing member 20.

The numeral 21 indicates a threaded disk or locking-nut received upon the hollow threaded stem 19, the former being countersunk on the under side and adapted to receive a leather washer 22 which is provided with internal screw-threads, thereby effecting a tight fit between the stem and the locking-nut 21.

Leading from the base 17 is a feed-pipe 23, to the outer end of which is connected a burner support consisting of a hollow upright portion 24 somewhat enlarged at the upper end thereof, forming an oil chamber 25, which is preferably provided with a removable cap 26. This cap may or may not be transparent, the purpose being to provide adequate means for determining the oil level within the chamber 25.

The numeral 27 indicates a burner provided with an annular oil groove 28. Extending horizontally from the oil chamber 25 is an oil duct 29 provided with a small central bore 30, said bore preferably in line with the bottom of the annular oil groove 28. As shown in Fig. 5, this oil duct may

be in the form of a tube 29', having arranged therein a plug 30' having a longitudinal slot 31' acting in the same capacity as the opening 30.

5. As a means for cleaning the oil duct 29, I preferably arrange an opening 31 diametrically opposite thereof in the chamber 25, which, however, is normally closed by a plug 32, the removal of the plug permitting 10 of an instrument being forced into the opening 30 for cleaning purposes.

As a further convenience, the plug 32 may be replaced with a drip-cock for draining off the chamber 25, should the oil rise suddenly.

15. In Fig. 4 is disclosed a modified form of the oil container or reservoir 1, wherein the upper compartment 1' is removably suspended within the main oil container 1, and 20 the float or valve-controlling mechanism 11' is located therebeneath, both elements being readily removable.

In operation, the reservoir 1 is adjusted to such a height with respect to the supporting base as to bring the oil in the compartment containing the float on a level with the opening in the oil duct 29 adjacent the burner, at which level the ball-valve is seated upon the valve-seat 10, cutting off the 25 flow of oil to the lower compartment. To vary the height of oil in the float compartment and the oil chamber 25, it is only necessary to adjust the height of the reservoir 1 with respect to the base 17. To reduce the 30 oil level in the float chamber, a lock-nut 21 is unscrewed, and the container or reservoir 1 is screwed down or turned to the right, while raising or turning to the left will increase the height of the oil in the float 35 chamber, and correspondingly increase the flow of oil to the burner, or rather increases the height of the oil in the chamber 25.

40. When the proper height is determined, lock-nut 21 is screwed down, holding the container 1 in the adjusted position. It will be observed that the pressure of the oil is against 45 the closing movement of the ball, thereby effecting a very sensitive and reliable action.

I claim:

50. 1. A heater comprising a burner adapted to burn a liquid fuel, a reservoir consisting of an upper and lower compartment, a filtering means arranged in the bottom of the upper compartment, and a regulating means arranged in the lower compartment for regulating the supply of fuel to the burner.
55. 2. A heater comprising a burner adapted to burn a liquid fuel, a reservoir for the

liquid, a hollow threaded stem supporting the reservoir, a base having a vertical hollow 60 threaded portion in which said stem is adjustably received and means for holding the stem and the reservoir in any desired adjusted position for controlling the level of oil supplied to said burner. 65

3. A heater comprising a burner, a reservoir and an oil chamber, bases for the reservoir and for the oil chamber, connection from the base of the reservoir to the base of the oil chamber, a vertical connection extending between the oil chamber and the base thereof, a horizontal feed line extending from the oil chamber to the burner and sight feed means in said oil chamber for determining the flow of the fuel therethrough. 70 75

4. A heater comprising a reservoir having an upper and lower compartment, a burner, an oil chamber, a feed pipe connecting the lower compartment of the reservoir to the oil chamber, a feed pipe leading from 80 the upper part of the oil chamber to the burner and means arranged in the lower compartment of the reservoir for maintaining a given oil level in said lower compartment of the reservoir and said oil chamber. 85

5. A heater comprising a base, a reservoir consisting of upper and lower compartments arranged above said base, a burner, an oil chamber, a feed pipe connecting the lower compartment of the reservoir to the oil 90 chamber, a feed pipe leading from the upper part of the oil chamber to the burner, means arranged in the lower compartment of the reservoir for maintaining an oil level in said lower compartment and said oil chamber 95 and means for regulating the height of the reservoir relative to the base for changing the level of the oil from the lower compartment of the reservoir with respect to the oil chamber adjacent the burner. 100

6. A heater comprising a reservoir consisting of upper and lower compartments, a burner, an oil chamber adjacent to the burner, a pipe arranged horizontally between said chamber and burner, a feed-pipe connected to the lower compartment of the reservoir and the oil chamber, means arranged in the lower compartment of the reservoir for maintaining a given oil level in said lower compartment and the oil chamber adjacent the burner, and a sight-feed arranged in said oil chamber for determining the oil level therein. 105 110

In testimony whereof I hereunto affix my signature.

HENRY M. SHEER.
